INTERNAL COMBUSTION ENGINE

Donald J. Campbell, Spring Lake Township,
Ottawa County, Mich., assignor to Campbell,
Wyant & Cannon Foundry Company, Muske-
gon Heights, Mich., a corporation of Michigan

Application October 24, 1932, Serial No. 639,218

2 Claims. (Cl. 123—90)

This invention relates to internal combustion engines, and is particularly concerned with improvements in such engines of the Diesel or semi-Diesel type where the fuel is injected into very highly compressed air within a combustion chamber, the air having its temperature raised to a point where it will spontaneously ignite the fuel.

In the present invention it is designed to produce a more nearly perfect combustion of the fuel charge and increase the power of output for a given size engine; also to eliminate smoke, carbon and the like from the exhaust products of combustion when the same are discharged from the engine. It is particularly designed that the fuel charge entering into the compressed air shall mix with pure air freed from any products of combustion produced by the preceding explosion.

Other objects and purposes than those enumerated will be apparent upon an understanding of the invention had from the following description, taken in connection with the accompanying drawings, in which,

Fig. 1 is a fragmentary vertical section of the upper portion of an engine made in accordance with my invention, and taken on the plane of line 1—1 of Fig. 3.

Fig. 2 is a fragmentary underplan view of the engine covering head over the cylinder of the engine.

Fig. 3 is a plan view of the engine covering head for a single cylinder engine.

Fig. 4 is a vertical section substantially on the plane of line 4—4 of Fig. 3.

Fig. 5 is a horizontal section substantially on the plane of line 5—5 of Fig. 1, and

Fig. 6 is a vertical section through a modified form of cylinder covering head construction.

The section lines are all taken as looking in the directions indicated by the arrows, and like reference characters refer to like parts as indicated in the drawings.

In the illustration in the drawings, the invention is shown as applicable to a single cylinder though it is, of course, to be understood that for multiple cylinder engines the construction with respect to each cylinder is merely duplicated. The cylinder 1 has an inner cylinder sleeve 2 and space 3 for water circulation therebetween as shown in Fig. 1, and within the sleeve 2, a piston 4 is mounted for reciprocation.

The covering head 5 for the cylinder is a casting cored out to provide water circulation chambers and passages 6 and secured to the cylinder

by means of the usual cap screws 7. At the central portion of the head directly over the center of the cylinder a combustion chamber receiving member 8 is integrally cast with the head, in which a separable combustion chamber member 9 is adapted to be secured. This combustion chamber 9 is formed at its inner side with a plurality of spiral grooves 10 separated by ribs. The lower end of the member 9 is open and the lower side of the head 5 is open to correspond and has downwardly and outwardly flared conical sides in which tangential grooves 11 are made, the purpose of which will be hereafter pointed out.

The combustion chamber member 9 is detachably secured and held in place within its receiving member 8 by an auxiliary head 12 located over and bearing on the same and secured to the head 5 by screws 7a. This head carries an injection means 13 used with Diesel engines by means of which liquid or other suitable fuel may be pumped and injected into the combustion chamber 9.

The auxiliary head 12 also is supplied with an air inlet valve 14 at the lower end of a valve stem 15 which is guided through a guide sleeve 16, the valve being normally held in closed position, as shown in Fig. 1, by a relatively heavy compression spring 17.

To operate and open the valve 14 a vertical rod 18 is operated by the usual and well known cam shaft of the engine, guided through a vertical guide 19, preferably integral with the head 5, and at a short distance below its upper end, equipped with a collar 20 which has downwardly and outwardly inclined conical sides. The outer end of the valve stem 15 is borne against by the free end of one arm 21 of a pivotally mounted lever, the other arm 22 of which extends alongside the upper portion of the rod 18 and carries a roller 23 at its outer end which rides against the inclined outer sides of the collar 20, whereby on upward movement of rod 18 the arm 21 is turned in a counterclockwise direction opening the valve 14.

The upper end of the rod 18 bears against the underside of the outer end of an arm 24 of a second lever pivotally mounted on and above the engine head, it having a second arm 25, the free end of which carries an adjustable screw 26 to bear against the upper end of a valve stem 27 which, likewise, is normally held in upper position by a coiled spring 28 and which is vertically guided through a guide sleeve 29. The lower end of the stem carries a valve 30 located in the lower side of the head 5, whereby air can be drawn into

the cylinder simultaneously with air passing by the valve 14 into the combustion chamber.

Each cylinder is also equipped with two exhaust valves, preferably, each at the lower end of 5 a valve stem 31 held in upper position normally by a spring 32. The upper ends of the stems 31 are underneath the lower side of an arm 33 of a pivotally mounted lever, the oppositely extending arm 34 of which, at its outer end, comes above 10 a second rod 35 (Fig. 5), similar to the rod 18, and similarly actuated by the rotating cam shaft of the engine. The head 5 is provided with an air inlet port 36 to carry air so that the same may pass by the valve at the lower end of the stem 15 27 when the valve is opened; and the auxiliary head 12 is provided with a branch port 36a so that the air may come to the opening normally closed by the valve 14 for passage of air into the combustion chamber when valve 14 is moved to 20 open position. Likewise there is an exhaust passage 37 for carrying away the products of combustion when the same pass by the exhaust valves on opening the same.

In the operation of the engine, during the 25 downward suction stroke of the piston 4, the main air valve at the lower end of stem 27 is opened and, simultaneously, valve 14 is opened whereby air is drawn into the cylinder and simultaneously into the combustion chamber 9. The smaller supply of air drawn into the combustion chamber 9 serves to cleanse and scavenge the combustion chamber of any gaseous products of combustion which remain in the chamber from a previous explosion. When the piston 4 reaches its lower- 30 most point of movement on the suction stroke the valves are closed, and on the succeeding upward stroke of the piston the air is very heavily compressed with a consequent raising of the temperature of the air to a very high degree. Substantially at the extreme upward movement of 35 the piston and at the highest point of compression of the air, fuel is injected into the combustion chamber through the injection means 13 and is spontaneously ignited. The piston 4 thereupon moves downward in the working stroke of the engine and the burning mixture of fuel and air passes from the combustion chamber into the cylinder. By reason of the swirling movement given to the burning charge from the spiral 40 grooves 10 and the radial downwardly and outwardly extending grooves 11 described, the burning charge is spread completely over the upper

side of the piston and continues its burning until the fuel is consumed with an increased degree of combustion to more nearly attain perfect combustion. The scavenging of previous products of combustion from the combustion chamber insures a better and more perfect combustion of the mixed air and fuel than would otherwise take place, this resulting in higher efficiency of the engine.

In Fig. 6 the removable and replaceable combustion chamber member 9 is replaced by an 10 internal combustion chamber member 9a cast with the head 5, it having the spiral grooves 10 at the inner side, open at its bottom and joining with the downwardly and outwardly flared and grooved inlet to the cylinder. It is preferred 15 to make the combustion chamber a separate member, as shown in Fig. 1, in order that the same may be replaced when necessary, it being apparent that the very high temperatures to which the combustion chamber is subjected may 20 eventually cause the same to burn out or crack so that ready and easy replacement is very desirable. This combustion chamber 9 is made of a high heat resisting material so that its effective life is lengthened but at the best its effective life 25 is not likely to equal that of the other parts of the engine so that replacement at times is desired.

The construction described is very practical and efficient, readily manufactured and with which substantially homogeneous intermixture 30 of the fuel with pure air and a substantially perfect or at least a very much increased degree of fuel combustion is attained. The invention is defined in the appended claims and is to be considered comprehensive of all forms of structure 35 coming within their scope.

I claim:

1. In a construction of the class described, two valves, springs for closing the valves, a lever of the first class having one end riding against one 40 of said valves to open the same upon movement of the lever, a reciprocatable rod engaging the other end of the said lever to operate the same, a collar attached to the reciprocatable rod, said collar having an outwardly extending surface 45 and a second lever of the first class having one end engaging the other of said valves and the other end riding against the said outwardly extending surface.

2. A construction as recited in claim 1 in which 50 the collar is of conical shape.

DONALD J. CAMPBELL.
